UNITED STATES PATENT OFFICE.

HAROLD R. WELLMAN, OF RIVERSIDE, ILLINOIS, ASSIGNOR TO WESTERN ELECTRIC COMPANY, OF CHICAGO, ILLINOIS, A CORPORATION OF ILLINOIS.

ADDING-MACHINE ATTACHMENT.

No. 882,806.

Specification of Letters Patent. Patented March 24, 1908.

Application filed September 30, 1905. Serial No. 280,741.

To all whom it may concern:

Be it known that I, HAROLD R. WELLMAN, citizen of the United States, residing at Riverside, in the county of Cook and State of

5 Illinois, have invented a certain new and useful Improvement in Adding-Machine Attachments, of which the following is a full, clear, concise, and exact description.

My invention relates to calculating machines, and has for its object the provision of 10 means for electrically controlling the operation of the shaft which actuates the calculating and recording mechanisms.

In my invention the shaft for operating 15 the calculating and recording mechanisms is preferably connected through a crank arm and a connecting rod to a gear wheel which makes one revolution for each momentary depression of a finger key. This gear wheel 20 is operated by a motor, which is in circuit with a pair of contacts adapted to be closed by means of said finger key, but so arranged that when the mechanism has once started to operate, the control of the contact points 25 is transferred to the mechanism itself, and hence the motor circuit is automatically controlled thereby.

A further feature of my invention consists 30 in means for automatically opening the circuit of the motor when the driving shaft of the calculating machine is in an inoperative position, said means being unresponsive under normal operation of the machine.

My invention also provides for an adjust- 35 ability of the parts, whereby compensation is made for currents of different voltages.

These and other features of my invention 40 will be more readily understood by reference to the accompanying drawings, in which, Figure 1 is a front elevation of the mechanism comprising my invention with the casing 45 thereof in section, the parts being shown in their normal or idle position; Fig. 2 is a similar view, showing the extreme position of the parts in driving the rock shaft; Fig. 3 is a 50 front elevation, with parts broken away, showing the operation of my invention when the switch is closed during the time the rock shaft is locked against rotation; Fig. 4 is a detail view of the lever arm which is secured to the rock shaft; Fig. 5 is a fragmentary front elevation of a comptograph machine and its support, parts being broken away, my invention being attached to one side thereof 55 and shown in end elevation with the casing

in section; Fig. 6 is a diagram of the circuits employed in my invention; Fig. 7 is a detail view, with parts broken away, showing means for locking the rock shaft.

Like characters of reference refer to like 60 parts throughout the several views.

The casing A, within which the mechanism constituting my invention is conveniently assembled, is attached at one side of the ordinary comptograph machine B, as indicated in Fig. 5. The rock shaft 1 of said machine constitutes as usual the means for operating the calculating and recording mechanisms. Fixed to the end of this shaft is one end of a crank 2, shown in detail in Fig. 4, the other end of said crank being pivoted at 2^a to lever 3, one end of which is in turn pivoted to the end of a rod or link 4. The other end of the rod 4 is pivoted at 4^a to a spur wheel 5, and is adjustable in length as well as being adjustably pivoted to said spur wheel. The gear wheel 5 meshes with the pinion 6 on the end of the armature shaft of the motor, the casing of which is indicated by the numeral 7. It is apparent, therefore, 80 that when the motor armature is rotated, the pinion 6 drives the wheel 5, and that the link or rod 4 is operated thereby. A stiff coiled spring 20 has its opposite ends connected to the free end of the lever 3 and a lug 2^b on the lower end of arm 2. The tension of said spring is adjustable by a screw 5^a, and is sufficient to make the lever 3 unresponsive to the pull of the link 4 under normal operation of the machine; that is, if the shaft 1 is free 90 to rock, for each revolution of the spur wheel 5, the lever 4 will operate the crank arm 2 and rock said shaft, as shown in Fig. 2, in one direction approximately through an arc of 45° and return it to its normal position 95 shown in Fig. 1. Under certain conditions, it is desirable that the shaft 1 of the calculating machine be locked, as for example when in the use of single sheets of paper the end of the sheet has been reached and 100 there remains no paper to record the operations. It has, therefore, been customary to provide calculating machines with means for locking the shaft which drives the registering and recording mechanisms.

I have shown in Fig. 7 the shaft 1 provided with a segment 22 having teeth 23, adapted to be engaged by a dog 24 under certain conditions in the operation of the calculating machine. Such well known 110

means for locking the shaft form no part of my present invention, and being fully shown and described in United States patent to Dorr E. Felt, No. 694,955, granted March 11, 5 1902, further description is deemed unnecessary.

In my invention when the shaft 1 is locked, the crank arm 2 is not free to move, and hence additional pull is made upon lever 3, 10 sufficient to overcome the tension of the spring 20. The lever 3 will be then pulled up to the position shown in Fig. 3, and will thereby open the circuit through the motor armature and prevent the operation of the 15 driving mechanism, as will be hereinafter more fully described.

An approximately U-shaped frame 8, of insulating material, braced by a strip 8^c is secured to the crank arm 2 by screws 8^d. 20 The frame 8 has opposing contacts 8^a and 8^b, between which operates a switch arm 9, pivoted to the lower portion of the frame 8. This switch arm 9 is controlled by the bell crank lever or switch member 10 pivoted at 25 10^a to the rod 4. The lower end of the lever 10 has secured to it one end of a coiled spring 11, the other end of which is secured to an insulating disk 12 carried by the switch arm 9. This structure provides a snap 30 switch controlled by the movement of the lever 10. The particular form of snap switch shown is not my invention, and other forms of switch may be substituted therefor.

Secured to the contacts 8^a, 8^b and switch 35 arm 9 are the terminals of conductors leading from the brushes *a*, *b*, *c*, respectively, which are clamped against the arm 2 by a strip 16. The brushes *a*, *b*, *c*, are adapted to move over arc-shaped metallic segments S, S', S², re- 40 spectively, mounted upon an insulated block secured to the casing A.

Pivoted upon a pin 13^c, near the upper end of the casing A, is a tripping lever 13, the movement of which is limited by its 45 jaws 13^a, located on opposite sides of a pin 14. This lever is normally held up by a spring 13^b, but may be depressed by pushing down a finger key 15 projecting through the casing A, and accessible to the operator. 50 When so depressed the lever 13 engages the switch member 10 and operates the same to throw the switch arm 9 against contact 8^b, thus closing the circuit through the motor armature, as clearly shown in Fig. 6, and 55 as will hereinafter be more fully described. A restoring lever 17 is also pivoted on the pin 13^a. The upper end of said lever is similar in form to the corresponding end of lever 13, and has jaws 17^a on opposite sides 60 of pin 14. A spring 17^b coiled about the pin 13^a, has one end secured to the lever 17 and the other end passed beneath the pin 14, thereby normally holding the lever 17 in the position shown in Fig. 1. The restoring 65 lever 17 is separate from the lever 13, and is

not under the direct control of the operator, the operation of the parts to open the circuit being automatic. The continued depression of the key 15 will not result in damage to the machine, but will merely 70 result in a repetition of the operation of the rock shaft 1.

A flange 17^c on the lever 17 projects in the path of a roller 10^b carried by the upper end of the switch member 10. When the 75 rotation of the spur wheel 5 draws down the link 4, carrying with it the lever 10, the roller 10^b engages the under side of the inclined surface of the flange 17^c and pushes it upward out of the path of the lever 10 as 80 shown in dotted lines in Fig. 2. When the flange is released from the roller, the spring 17^b returns the lever 17 to normal position. As the spur wheel 5 completes its revolution, the roller 10^b rides over the upper inclined 85 surface of the flange 17^c, as shown in dotted lines in Fig. 2, thereby automatically operating switch member 10 to open contact 8^b and close contact 8^a.

A button 18, mounted on the gear wheel 90 5, and adapted to be adjusted at different radial positions thereon, is adapted when the said gear wheel is in certain predetermined positions to ride over a spring 19 and thereby 95 to close the contact of said spring with a spring 19^a, for purposes hereinafter set forth.

I preferably employ a compound wound motor, as indicated in Fig. 6, in which R and R' represent the series and shunt windings respectively. When the switch 21 is closed 100 the current flows from the positive terminal through the series field R and the shunt field R' of the motor, including the lamp resistance L to the negative terminal. With the switch arm 9 in the position shown in 105 Fig. 6, the motor armature M receives no current, since the circuit is open at 8^b. However when the switch arm 9 engages contact 8^b, a circuit is closed from the positive terminal through motor armature M, 110 segment S², switch arm 9, contact 8^b, segment S', to the negative terminal. This operates the motor armature, which, as above stated, through the pinion 6, rotates the gear wheel 5. The button 18 rides off 115 the spring 19 and breaks its contact with spring 19^a. When the wheel 5 has almost completed one revolution the switch 9 is moved from contact 8^b to contact 8^a in a manner hereinbefore described. Approximately simultaneous with this operation, however, the button 18 again closes the contact of springs 19 and 19^a. A local circuit is thus closed from one terminal of the motor armature through segment S^a, switch arm 9, contact 8^a, segment S, springs 19^a and 19 to the other terminal of the motor. The function 120 of this closed circuit is to check the further rotation of the armature M, due to momentum previously acquired. This dynamic 125 130

brake effect, as is apparent, is due to the fact that with the local circuit closed, the motor in effect becomes a generator, and hence offers increased resistance to further 5 rotation. As before stated, the length of the rod 4, its point of connection to the gear wheel 5, and the position of the button 18 on said spur wheel is adjustable, thus compensating for currents of different voltages, 10 by providing for such adjustment as will cut the motor out of circuit and introduce the means for overcoming the momentum of the parts, permitting the motor armature, however, to rotate the spur wheel 5 a sufficient 15 distance to restore the parts to normal positions.

Briefly, the operation of my driving mechanism is as follows: When it is desired to actuate the recording mechanism of the calculating machine, the finger key 15 is depressed, thus depressing the tripping lever 13, which 20 in turn operates the bell crank lever or switch member 10 and operates the switch arm 9 to close the circuit through the motor armature. 25 The revolution of the armature shaft causes the pinion 6 keyed thereon to drive the spur wheel 5. During the first part of a revolution of the spur wheel 5, the rod 4 is drawn downward, and through the lever 3 and 30 crank arm 2, rocks the driving shaft 1 of the calculating machine through an angle of approximately 45°. Upon the return stroke of the rod 4 the lever 10 is actuated by the restoring lever 17 to open the contact 8^b and 35 close contact 8^a. The closing of contact springs 19 and 19^a by the button 18 tends to retard the rotation of the armature M, the parts being adjusted, however, so that the momentum acquired is sufficient to restore 40 them to their normal positions. If, for any reason, the shaft 1 is locked so that the crank 2 cannot be operated, the pull of the rod 4 on the lever 3 will overcome the tension of spring 20, and will operate said lever so that 45 a lug 3^a thereon will engage with a lug 10^c on the lever 10, thereby operating said lever to at once open the circuit at 8^b. The tension of the spring 20 will thereupon reset the parts to their normal positions.

50 What I claim is;

1. In a calculating machine, the combination with the driving shaft thereof, of a crank arm connected to said shaft, a motor, a circuit therefor a gear wheel driven by said motor, a rod connecting said gear wheel and crank arm, a switch carried by said crank arm for cutting said motor in or out of circuit, and a key accessible to the operator of the machine for closing said switch.

60 2. In a calculating machine, the combination with the driving shaft thereof, of a crank arm secured on said shaft, a motor, a circuit therefor a switch carried by said crank arm for cutting said motor in or out of circuit, an 65 operator's key for closing said switch, and

means driven by the motor for operating said crank arm, substantially as described.

3. In a calculating machine, the combination with the driving shaft thereof, of a crank arm connected to said shaft, a gear wheel, 70 a rod connecting said gear wheel and crank arm, a motor for driving said gear wheel, a circuit for said motor a switch arm carried by said crank arm, a switch member pivoted to said connecting rod and adapted to operate 75 said switch arm to open or close the motor circuit, a finger key, a tripping lever actuated by said key to engage the switch member and thereby close the switch, whereby said gear wheel makes one revolution for a momentary depression of said key, and a restoring lever in the path of movement of the switch member and adapted to operate the same on the return stroke of the connecting rod to open the switch, substantially as described. 80

4. The combination with a driving shaft of a calculating machine, of a crank arm secured on said shaft, a motor, a circuit therefor means driven by the motor for rocking said 90 crank arm, said means being adjustable to compensate for currents of different voltages, a switch mounted on the crank arm for cutting said motor in or out of circuit, a finger key for closing said switch, and a restoring 95 lever adapted to open the switch on the return stroke of the crank arm.

5. The combination with a calculating machine provided with registering and recording mechanisms, a shaft for driving the same and 100 means for locking the shaft, of a crank arm secured on said shaft, a lever pivoted on said arm, a gear wheel, a rod connecting said gear wheel and lever, a motor for driving the gear wheel, a circuit for said motor a switch for cutting the motor in or out of circuit, and 105 a spring connecting the lever and crank arm, the tension of said spring preventing the movement of said lever on the arm during the normal operation of the shaft, but said lever 110 being responsive to the pull of said rod to open the switch when said shaft is locked.

6. The combination with a calculating machine provided with a driving shaft and means for locking the same, of a motor, a circuit therefor an arm on said shaft, a lever pivoted to said arm, a yielding connection between the free end of said lever and arm, a connection between said lever and motor for operating the arm, a switch for closing the 120 circuit of the motor, said switch being arranged to be operated by the yielding of said lever when the shaft is locked.

7. The combination with a driving shaft of a calculating machine, a motor, a circuit 125 therefor connection between said motor and said driving shaft, a pair of contacts, a switch arm for said contacts the movement of which in one direction closes a circuit to rotate the motor armature and the movement in the 130

reverse direction closes a circuit which acts to overcome the momentum of the parts, substantially as described.

8. The combination with the driving shaft of a calculating machine, of a crank arm secured on said shaft, a lever pivoted at the upper end of said arm, a coiled spring connecting one end of said lever with the lower end of said arm, a gear wheel, a rod connecting said gear wheel and said lever, a motor for driving said gear wheel, a circuit for said motor a pair of opposing contacts and a switch arm carried by said crank arm for controlling the circuit of the motor, a switch member pivoted to said rod for operating the switch arm, a lever for tripping said switch member, a finger key for operating said tripping lever to close the circuit, and a restoring lever in the

path of movement of said switch member and adapted to operate the same to open the circuit during the return stroke of the rod, substantially as described. 20

9. The combination with the driving shaft of a calculating machine, of an electric motor for operating said shaft, and a switch carried by said shaft a circuit for said motor for controlling the closing and opening of the motor circuit. 25

In witness whereof, I hereunto subscribe my name this 27th day of September A. D., 30 1905.

HAROLD R. WELLMAN.

ROY T. ALLOWAY.

Correction in Letters Patent No. 882,806.

It is hereby certified that in Letters Patent No. 882,806, granted March 24, 1908, upon the application of Harold R. Wellman, of Riverside, Illinois, for an improvement in "Adding-Machine Attachments," an error appears in the printed specification requiring correction, as follows: After line 49, page 3, the following paragraph should be inserted:

The yielding connection between the motor shaft by which the circuit of the motor is adapted to be opened when the shaft is locked is not broadly my invention, and in view of the subject matter claimed in the co-pending application of Charles P. Wetmore, Serial No. 275,991, filed August 28, 1905, I hereby expressly disclaim the broad subject matter of said claims. So far as this feature is concerned, my invention relates only to the specific means hereinafter set forth in the claims.

and that the said Letters Patent should be read with this correction therein that the same may conform to the record of the case in the Patent Office.

Signed and sealed this 14th day of April, A. D., 1908.

C. C. BILLINGS,
Acting Commissioner of Patents.
